UNITED STATES PATENT OFFICE.

JEROME W. ROPP, OF ELYRIA, OHIO.

CHAPE FOR HALTERS.

SPECIFICATION forming part of Letters Patent No. 367,238, dated July 26, 1887.

Application filed January 23, 1887. Serial No. 925,826. (No model.)

To all whom it may concern:

Be it known that I, JEROME W. ROPP, a citizen of the United States, residing at Elyria, in the county of Lorain and State of Ohio, have 5 invented a new and useful Chape for Halters, of which the following is a specification.

My invention relates to chapes or clamps for securing the web or cloth strips composing the headstalls of halters for horses or other 10 animals; and the object of my invention is to provide such a chape or clamp of metal as will effectually hold the strips of webbing or cloth, be easily and cheaply applied, and when on 15 make a strong and durable fastening. I attain these objects by means of the mechanism illustrated in the accompanying drawings, in which—

Figure I represents a headstall of an ordinary halter to which my invention has been 20 applied. Fig. II represents the top or outside view of one half of my invention. Fig. III represents the bottom or inside view in perspective of the other half of my invention.

Similar letters refer to similar parts throughout the several views.

A represents a metallic plate of the form represented in the drawings. In one end of same is cut the opening a.

b represents teeth in the edges of said plate 30 and standing at about right angles with said plate.

c represents ridges or corrugations formed on the inside of said plate and running parallel to the teeth along the edges. I do not 35 intend to confine myself to any form of ridges or corrugations, as my plates may be constructed with diamond or other shaped points with corresponding depressions; but I prefer the form shown in the drawings.

40 i i represent holes for rivets through each of said plates.

The plates A are used in pairs, and the pair is so constructed that when placed together evenly the teeth of one plate fit or fall into the 45 depressions between the teeth of the other, and the ridges of one plate fit into the hollows between the ridges of the opposite plate, and vice versa.

The operation of my invention is as follows,

to wit: The side pieces of webbing or cloth to 50 a headstall are cut out the proper length, also the nose-piece, and crossed at their ends at right angles. One plate of my metallic chape is placed under same, so that the teeth along the edges will rest under and across each piece 55 or strip of webbing or cloth. Then the other plate of my metallic chape is placed immediately over the under piece and rivets passed through the holes in the plates and webbing or cloth between, and the plates forcibly drawn 60 together and the rivets headed. The teeth in the edges of the plates and the ridges or corrugations of same fitting into the openings or hollows of its opposite plate effectually clamp and retain the ends of said webbing or cloth 65 without cutting or injuring the same.

The opening a, with the surrounding part of the plate, forms a convenient and suitable place for securing the chin strap.

By means of my invention I save the use of 70 a ring on each side of the headstall, also the sewing and leather necessary to form an ordinary chape.

Having fully described my invention, what I claim as new, and desire to obtain by Letters 75 Patent of the United States, is—

1. A metallic chape for web or cloth halters for animals, consisting of the plates A, provided with the teeth b on the two sides thereof at nearly right angles to each other, and the 80 opening a, all as above set forth, and substantially as described.

2. A metallic chape for halters, consisting of two plates, A, provided with the teeth b, in combination with the ridges or corrugations c, so constructed that the teeth and corrugations of one plate will project inward toward those of the opposite plate, all as above set forth, and substantially as described.

3. The plate A, provided with the teeth b, 90 in combination with the corrugations or ridges c, all as above set forth, and substantially as described.

JEROME W. ROPP.
